TO A. C. LAWRENCE LEATHER COMPANY, OF BOSTON, MASSACHUSETTS, A CORPOR-
ATION OF MAINE

STRETCHING MACHINE

Application filed March 31, 1928. Serial No. 266,365.

The present invention relates to stretching machines and more particularly to power operated machines designed especially for stretching leather, hides, or skins.

5 One of the objects of the present invention is to provide a power operated machine of simple and inexpensive construction for stretching leather hides or skins or other like material in an expeditious and exact manner.

10 Another object of the invention is to provide a power operated machine whereby varying amounts of stretch may be imparted to the material in different directions and in different portions thereof, according to the skill and judgment of the operator and dependent upon the size and character of the material and the result desired.

15 20 With these and other objects in view, as will be apparent to those skilled in the art, the present invention consists in the devices and combination of devices hereinafter described and claimed.

25 The invention in its preferred form is illustrated in the accompanying drawings in which Fig. 1 is a top plan view of the machine showing a corner portion of the expandible frame to which the hide or other material to be stretched is attached; Fig. 30 30 35 40 45 50 55 60 65 70 75 80 85 90 95 100 2 is a front elevation of the machine with the expandible frame in position and a portion thereof shown in section; Fig. 3 is a top plan view of the extensible frame showing the manner of attaching a hide; Figs. 4 and 5 show a top and side view, respectively, in detail of the toggle, toggle cord, and cleat used in securing a hide to the frame; Fig. 6 is a detail elevation of a portion of the machine showing one of the dogs which engage the frame to which the hide is attached, together with its actuating screw and limit switches; and Fig. 7 is a schematic diagram of motors, controls, and associated circuits employed in actuating the machine.

The apparatus illustrated in the drawings comprises, briefly, an expandible frame within which the hide is secured, and a machine for expanding such frame and thereby stretching the hide, the frame having pro-

vision for maintaining its expanded condition so that it may be removed from the machine for the drying or other treatment of the hide and the expanding of another frame by the machine.

55 The expandible frame is shown in Fig. 3 and comprises the four frame members or bars 11, having at each end the overlapping, longitudinally arranged slots 12, through which extend the bolts 13 with suitable washers and locking nuts. The slots 12 permit the expansion and contraction of the frame as desired when the nuts are loosened. Thereafter, by tightening the nuts the frame is held fixedly in the adjusted 60 65 70 75 80 85 90 95 100 position.

The hide or similar material to be stretched is fastened inside the frame by means of toggles or clasps 16, which may be of any of the well known and familiar constructions. These toggles grip the hide near its edge and are connected to the frame by means of cords 18 fastened in the cleats 20 on the frame members.

Preparatory to mounting a hide in the 75 frame, the latter will be contracted, preferably to its minimum size so as to permit a sufficient range of expansion to provide the desired degree of stretch. The parts are then secured in position by tightening the 80 nuts. The hide is next mounted in the frame by means of the toggles and cords, the latter being drawn and fastened with the desired tension so as to extend the hide flat and smooth under a uniform low tension in all directions.

The frame and hide are now ready for the stretching machine. This comprises movable shoulders or dogs which engage with the inner edges of all four members of the 90 frame and are moved apart by means of threaded shafts driven by electric motors.

This mechanism is carried upon the machine frame which is composed of the several horizontal members 22 connected together with angle brackets and having corner posts 24. Secured upon the top of the frame members are the flat bearing supports 26 to which are fixed the bearing 28 for the several threaded shafts. These are four 100

in number and are arranged horizontally in the form of a square with their ends overlapping. Two of these shafts 30 and 32 are parallel to one another and are located on opposite sides of the machine, being driven by a single motor 34 through reduction gearing 36 and sprockets 38 and chain 40. The other pair of shafts, 42 and 44, at right angles to the first mentioned pair, are driven each by its own independent motor 46 and 48, respectively, with similar reduction gearing 50.

The outer end portions 52 of all four shafts between their outer bearings 28 are screw threaded and carry thereon the dogs 54 for expanding the hide-carrying frame. The threads on the opposite ends of a shaft are oppositely formed, i. e. one a right-hand and the other a left-hand thread, so that when the shaft is rotated in one direction the dogs will be moved apart, and when rotated in the opposite direction the dogs will be drawn together. The threads on shafts 30 and 32 are so arranged that when the motor 34 is operated in one direction all four of the dogs on these shafts move outwardly to the ends, and when the motor is reversed they move inwardly.

In order to maintain the dogs in proper vertical position during their inward and outward movement along the threaded shafts, each dog is provided with a depending foot 56 having a circular hole 58 to receive the guide rod 60 mounted in the vertical supports 62 and 64.

The expandible hide-carrying frame is supported above the several shafts and their actuating mechanism upon the horizontal arms 66 extending outwardly near the corners of the machine. Preferably these arms are arranged in pairs on opposite sides of the machine so that the two opposite bars only of the expandible frame will be supported, the other two bars being carried by the first mentioned bars. This arrangement is desirable owing to the fact that the two pairs of bars do not lie in the same plane.

In the stretching of many materials the amount of stretch desired will vary, not only in direction but also in different portions, according to the character of the material, its intended use, etc. In the stretching of hides, different amounts of stretching will ordinarily be required along the backbone, across the neck, and across the butt. Accordingly, in the illustrated embodiment of the present invention, the motors imparting stretch to these parts are under separate and independent control whereby any desired extent of stretching movement may be given through the dogs actuated by one motor without affecting the dogs actuated by either of the other motors. Furthermore, in order to avoid loss of time these motor controls are so arranged that all their

motors may be simultaneously operated if desired, or any two of them. For the same reason the idle or reverse rotation of the motors to return the dogs to their inward or initial position is simultaneously effected and preferably through a single or common control.

The circuits and controls are illustrated schematically in Fig. 7, and comprise a three phase current supply indicated by the leads A, B, and C; the three motors marked D, E, and F; the three forward magnetic starters, one for each motor, indicated at FMS', FMS², and FMS³; the operating magnets therefor FOM', FOM², and FOM³; three reverse magnetic starters RMS', RMS², and RMS³; the operating magnets therefor ROM', ROM², and ROM³; three push button controls for the forward starters, one for each motor, indicated at PB', PB², and PB³; a single push button control for all three reverse starters PB⁴; three limit switches for forward movement, one for each motor, FLS', FLS², and FLS³; and a similar number of reverse limit switches RLS', RLS², and RLS³.

The electrical connections between these various parts are clearly shown on the diagram and need not be here described in detail. The limit switches are located as shown in Fig. 6, the forward switch FLS' being placed at or near the outward limit of movement of the dog 54 so that the depending foot 56 will engage and actuate the switch to stop the motor and prevent further outward movement of the dog. Similarly the reverse limit switch RLS' is placed at or near the limit of the inward or reverse movement of the dog.

Ordinarily the forward or outward limit switch is not brought into action, the operator having given sufficient stretching movement to the hide and stopped the motor before the extreme outward position is reached by the dog. The inward or reverse limit switch, however, operates on each reverse movement of the motor, being the only means for stopping such reverse movement.

The push button controls are located at some convenient position for the operator where he can stand and observe the stretching as it progresses. The connection through each of the forward push buttons is such that each must be held depressed in order to maintain its operating magnet energized and its forward magnetic starter in operation to supply current to its motor. Upon release of a button, the motor controlled thereby immediately stops, but may be started again by depressing its proper button if further stretching is desired.

The connections through the single reverse button and the reverse operating magnets are such that once the button is depressed and the magnets energized, they will remain

energized, notwithstanding the release of the button, until the reverse limit switches are engaged by the dogs and actuated thereby.

- 5 Thus the operator has complete and separate control over each of the motors during the stretching operation and may operate them simultaneously or consecutively and to any extent desired. After the stretching 10 has been completed and the stretching frame has been locked in its expanded position, the operator has only to depress momentarily the single reverse button, whereupon all three motors are set in reverse operation and each continues until it is independently stopped by its reverse limit switch.

In the operation of the machine the hide is first "toggled", that is, mounted in the 20 expansible frame by means of the toggles and their attaching cords, the frame being contracted at this time. The frame is then placed upon the machine with the "back-bone" of the hide, i. e. its longitudinal axis 25 from neck to tail, parallel to the pair of shafts which are actuated by the single motor and the clamping nuts are loosened.

The operator next depresses the button 30 controlling the motor and the dogs engaging the bars opposite the neck and tail exert a preliminary stretching lengthwise of the hide. When sufficient preliminary stretch has been imparted, the button is released and the other buttons are depressed 35 to stretch the hide transversely at the neck and the butt. This may be done simultaneously or consecutively as the operator desires, and further stretching may be imparted to the hide in any direction or amount as 40 the operator in his judgment shall deem advisable, until the hide has been properly stretched.

While the motors are stationary and the frame is held expanded, the operator 45 tightens the nuts upon the corner bolts and thus locks the frame in its expanded condition. The frame and its hide are then removed for drying or other treatment. A momentary depression of the reverse button 50 by the operator brings the parts automatically back to their original position ready for another frame and hide.

Thus a hide may be stretched by power-stretching devices in an expeditious and 55 exact manner, under the full control and judgment of the operator, according to the character of the hide, its intended use, etc.

While the present invention has been 60 shown and described as embodied in a machine for stretching hides, it is to be understood that it is not necessarily limited thereto but may be embodied in machines for stretching other materials. Nor is the present invention limited to the particular 65 forms and arrangements herein shown and

described but may be embodied in other and different forms and combinations within the language of the claims.

Having thus described the invention, what is claimed is:

1. A stretching machine having, in combination, a pair of threaded shafts disposed at right angles to one another, threaded dogs on the shafts, a motor for each shaft, and controlling devices for independently 70 controlling the operation of each motor in one direction and for commonly controlling the operation of both motors in the opposite direction.

2. A stretching machine having, in combination, a threaded shaft, a motor for actuating the same, a threaded dog mounted on the shaft, a switch for controlling the starting and stopping of the motor when the shaft is being actuated during the 80 stretching operation, a reverse switch for setting the motor in operation to actuate the shaft for its idle or return operation, and a stopping switch for automatically stopping the motor on the completion of such 85 idle operation.

3. A stretching machine having, in combination, a plurality of shafts, means having screw connections with the shafts for imparting a stretching action to the material to be stretched, and power-driven connections under the control of the operator for operating a portion of said shafts simultaneously, and others of said shafts independently to vary the extent and direction of 90 the stretching action.

4. A stretching machine having, in combination, horizontally extending supports on opposite sides of the machine for supporting an expansible frame, two pairs of horizontally disposed shafts positioned below the plane of said supports, the shafts of one pair being parallel and at right angles to the parallel shafts of the other pair, the shafts of each pair being widely spaced 95 apart, devices actuated by the shafts for engaging and expanding the frame, and power actuated means for rotating each pair of shafts independently of the other pair in one direction, and both pairs simultaneously 100 in the other direction.

5. A stretching machine having, in combination, devices for imparting stretching action to the work, power driven means for imparting longitudinal and transverse movements to said devices, and control mechanism for said means for independently controlling the longitudinal and transverse advance movements thereof and for commonly controlling the return movements thereof.

6. A stretching machine for expanding a stretching frame comprising four members to which the work is attached, said machine having in combination, devices for engaging each member of the frame at a plurality of 120

widely separated points, and moving such member outwardly to expand the frame and stretch the material, means for actuating the said devices including power driven mechanisms and controlling means therefor, one mechanism actuating simultaneously and uniformly the devices engaging one pair of opposite frame members to move all portions of said members outwardly the same distance, and a pair of mechanisms operat-

ing each independently of the other for actuating a portion only of the said devices for each of the other pair of frame members, whereby different portions of the latter pair of frame members may be moved different distances outwardly to vary the stretching effect at different portions of the frame. 70
